UNITED STATES PATENT OFFICE.

ELLIS HALE WILKINSON, OF BRISTOL, VIRGINIA, ASSIGNOR TO BRISTOL STOVE & FOUNDRY COMPANY, INC., OF BRISTOL, VIRGINIA, A CORPORATION OF VIRGINIA.

WATER HEATER.

Application filed November 19, 1923, Serial No. 675,739. Renewed August 3, 1925.

To all whom it may concern:

Be it known that I, ELLIS H. WILKINSON, a citizen of the United States, residing at Bristol, in the county of Washington and 5 State of Virginia, have invented new and useful Improvements in Water Heaters, of which the following is a specification.

The object of this invention is to heat the water in a tank or reservoir employed in 10 connection with a cooking range or the like, by providing circulation between the reservoir and a pipe extending through the lower portion of the flue at the back of the range.

A further object is to avoid excessive 15 heating of the water, which frequently occurs when a moderately hot fire is maintained and when the pipe providing for the circulation of the water extends into the firebox or connects with a water back or water 20 front in the fire box.

A still further object is to effect the desired result by direct and inexpensive construction, without change in the construction 25 of the stove or range, beyond the provision of openings in the flue indicated, for the insertion of the pipe.

With the foregoing and other objects in view, the invention consists in the novel construction and arrangement of elements described, illustrated, and claimed, it being understood that modifications may be made 30 within the scope of the claims without departing from the spirit of the invention.

In the drawings, Figure 1 is a view of a 35 range in rear elevation, with my improvement applied thereto; Figure 2 is a similar view of the range, with a portion of the rear smoke flue broken away to show a water pipe extending into this flue; Figure 3 is a view of the range in vertical longitudinal section, 40 showing how the rear flue is subjected to indirect heat from the firebox; Figure 4 is a vertical section on a plane perpendicular to the plane of Figure 3.

The flue 10 of a range of a standard type 45 is provided with the usual damper 11 and opening 12 for connection with a smoke pipe leading to a chimney. The lower portion of flue 10 communicates with a chamber 13 50 under the oven 14, and the chamber 15 above

the oven communicates with the fire box 16, and indirectly in the usual manner with lower chamber 13.

Openings are provided in the side wall of flue 10, below the damper, for the pipe 55 referred to below.

A reservoir or tank 18 is positioned at the side of the range remote from the firebox, and pipes 19 and 20 extend respectively from the side and bottom of the reservoir into 60 the flue 10, where they are connected by vertical pipe 21 and elbows 22, 23. Unions or couplings 24, 25, and drain cock 26 serve the usual purpose.

This particular connection with the rear 65 portion of the stove, and involving the flue carrying the products of combustion, has been found especially effective, and the water is kept at an even temperature, near the boiling point, with a moderate fire. 70

What I claim is:

1. In a device of the class described, a firebox, an oven at one side thereof, a chamber extending around the oven and having communication with the firebox, a smoke 75 flue in communication with the firebox and with the upper and lower portion of the chamber, a reservoir, and pipes extending from the reservoir and connected therewith at different levels, said pipes extending into 80 the flue, means in the flue connecting the pipes with each other, said means extending upwardly alongside a vertical wall of the oven, and a damper for diverting all products of combustion, from direct passage 85 to the flue, into contact with the bottom of the oven and thereafter around the pipes in the smoke flue.

2. The combination with a range including an oven and firebox, of a smoke flue 90 having permanent connection with the range at points above and below the oven, a reservoir, means for circulating water from the reservoir through the flue between said points of connection, and means for directing all products of combustion to the bottom of the oven and thereafter to said means for circulating water. 95

In testimony whereof I affix my signature.

ELLIS HALE WILKINSON.
